DIVIDING MACHINE

Mark A. Mattare, Arlington, Va., assignor to the
United States of America as represented by the
Secretary of the Interior

Application May 23, 1946, Serial No. 671,884

5 Claims. (Cl. 33—19)

(Granted under the act of March 3, 1883, as
amended April 30, 1928; 370 O. G. 757)

1

The invention described herein may be manufactured and used by or for the Government of the United States for governmental purposes without the payment to me of any royalty thereon in accordance with the provisions of the act of April 30, 1928, (Ch. 460, 45 Stat. L. 487).

My invention relates to dividing machines and particularly to one which is primarily used for scribing in an emulsified film on a glass negative a plurality of uniformly spaced graduations (or "ticks") adjacent to equally spaced "meridian" lines or "projections." My machine includes means for at will scribing lines of any one of a plurality of predetermined lengths, and on either or both sides of a meridian line and also means for at will varying the spacing of the graduations. With my machine it is also possible to mark a sensitized glass plate negative of a map with a scale based upon the recorded distance between two identifiable points.

In the accompanying drawings illustrative of a preferred embodiment of my invention—

Fig. 1 is a plan view, showing my device in operative position upon a glass negative.

Fig. 2 is a section taken on the line 2—2 of Fig. 1.

Fig. 3 is a section taken on the line 3—3 of Fig. 1.

Fig. 4 is an enlarged fragmentary plan of a portion of parts shown in Fig. 1, to more clearly illustrate my stop mechanism.

Fig. 5 is a detail of various combinations of marks inscribed by my device.

Fig. 6 is an enlarged transverse section taken on the line 6—6 of Fig. 1.

Fig. 7 is a greatly enlarged plan view of my scribe holder.

Fig. 8 is a detail of a detachable bracket used to limit the upward movement of my scribe while my device is in operation.

Fig. 9 is a detail section on line 9—9 of Fig. 1, showing the construction of the pivot on my adjustable space gauging lever.

Fig. 10 is a greatly enlarged horizontal section on the line 10—10 of Fig. 3, showing my spacing lever in engagement with a spacing pin.

In these drawings, a base plate 11 is provided with parallel tracks or rails 12 on the upper face of the base 11 on which tracks are mounted a two-part movable carriage 13, 14, the lower section 13 of which is provided with suitable grooves 15 and also with shouldered slots 16 for headed machine screws 17 which are threaded into the base 11 and serve to prevent accidental separation of the carriage 13, 14 from the base plate 11.

2

Two marginal guide bars 18 are rigidly attached to the lower section 13 of the carriage by screws 19 and guide the upper section 14 of the carriage as it is shifted.

5 Two spaced guide bearings 20 are rigidly secured to the lower carriage section 13 and each is provided with a removable cap 21 which is rigidly secured to the bearings 20 by screws 22. Each bearing 20 is provided with a locking plate 10 23 which is clamped against a carriage bar 24 by a set screw 25. A second set screw 26 in the cap 21 clamps the bar 24 against the bottom of the bearing 20, and with the set screw 25 serves to take up all lost motion between the bar 24 15 and bearing 20. A companion carriage bar 27 is connected to the bar 24 by terminal links 28 and 29 and is resiliently raised by coiled springs 30 operably connected to each link.

A scribe carriage 31, provided with a removable cap 32, is slidably mounted on the carriage bar 27 and is held by a locking plate which is pressed against the bar 27 by a thumb-screw 34. The scribe carriage 31 is provided with a slide 35, and a holding plate 33, a vernier thumb-screw 36 and a compression spring 37, the latter serving to resiliently oppose the thumb-screw 36. The horizontal portion 35—A of slide 35 is provided with a plurality of split sockets 38 and clamping thumb-screws 39 to permit the use of a plurality of sizes of scribe pins 40 (or a pencil or a "Leroy" pen, not illustrated).

When the machine is in use a detachable bracket 41 is secured to the carriage bar 24 by a locking thumb-screw 42 and limits the raising of the scribe pin 40 by the coiled springs 30.

35 The length and direction of the graduations is regulated by a movable stop bar 43 comprising offset portions 44 and 45 which are rigidly connected by a diagonal bar 46. The stop bar 43 is provided with a stop lug 47 and a handle 48. Rigidly attached to the base plate 11 are companion upwardly extending lugs 49 and 50 which extend into apertures 51 and 52 in the carriage section 13; these apertures are materially larger 40 than the lugs 49 and 50 to permit relative movement of the carriage with respect to the base plate 11.

45 The lug 49 is provided with a plurality of capstan-headed screws 53; 54; 55 and 56 which serve as adjustable stops. The companion lug 50 is also provided with a plurality of capstan-headed screws 57; 58; 59 and 60 which extend in the opposite direction to the first set of capstan-headed screws. Each of these adjustable stop

screws is provided with a capstan-type lock nut 61.

The lug 49 is provided with a recessed latch 62 which is frictionally held and is provided with an operating pin 63. A similar latch 62 in the lug 50 has an operating handle 62-A. The carriage 13 is provided with a latch-receiving recess 64 opposite the lug 49 and a similar latch-receiving recess 65 is opposite the lug 50, both recesses being wider than the latches 62 to permit restricted motion of the carriage 13, 14, with respect to the base plate 11.

A pinion 66 having a knurled head 67 is mounted on one of the guide bars 18 and meshes with a rack 68 rigidly secured to the upper section 14 of the movable carriage to provide a means for adjusting the size of the carriage 13, 14, while two knurled clamping screws 69 in companion slots 70 in the section 14 provide a means for clamping the section 13 to the section 14 of the carriage. A pinion 71 is supported in a bearing bracket rigidly attached to one of the guide bars 18 and is provided with an operating lever 71-A. To the base 11 there is attached a rack 71-B with which the pinion 71 meshes to move the carriage 13, 14, and the scribe pin 40 while two tension springs 72 connect the carriage section 13 to the base plate 11 and provide a resilient means for returning the carriage and the scribe pin to their initial positions.

At the mid-point of the carriage bar 24 there is pivoted a lever section 73 which is arranged to telescope within a tubular lever section 74. The latter is pivotally connected with the carriage section 14 by a pivot pin 75 and near the outer end of the lever section 74 an anti-friction roller 76 in a bearing 77 provides a freely movable support on the carriage section 14. A lever 78 is pivoted to the lever section 74 and is provided with a curved terminal claw 79 and a sighting hole 80 and is resiliently pressed by a compression spring 81. The carriage section 14 is provided with a plurality of upwardly extending pins 82, arranged in an arc, to which the lever 73, 74 is selectively locked by the claw 79, the latter being unlocked by downward pressure on the lever 78. The spacing of these pins is calculated to produce equal spacing of the "ticks" and therefore varies progressively each way from the mid-point of the arc. Two handles 83, which extend laterally from the base 11, serve to assist an operator to align my machine with a selected meridian or the like.

For operation, my device is aligned on an emulsified glass negative with the carriage bars 24 and 27 parallel with a selected line on the negative and the scribe pin 40 at a selected starting point. If a trial discloses that the initial setting of the machine makes spaces which are too wide, the telescoping lever 73, 74 is shortened by turning the pinion 66 and thereby reducing the size of the carriage 13, 14, and thereby also shortening the lever 73, 74. After the width of the spaces has been correctly adjusted, the scribe pin 40 is set approximately at a desired starting point and clamped with the thumb-screw 34; then with the aid of the vernier thumb-screw 36, the pin is accurately set at the zero point.

If the graduations are to be marked above the line, as illustrated at 84 in Fig. 5, the stops 53 to 56 (Fig. 4) are used with the latch 62 in the lug 49. The stop bar 43 is shifted until the lug 47 is in alignment with a selected stop, for example No. 54, the scribe pin 40 is then lowered and

pressed against the glass plate while it is reciprocated by the lever 71-A to cut a line in the coating, the pin being brought to rest when the lug 47 reaches the stop 54. Longer or shorter lines 5 may be cut by shifting the stop bar into alignment with another of the stops, for example, No. 53 or No. 55. The travel of the carriage and scribe pin 40 may also be restricted by using the latch 62 in the lug 50. Graduations 85 are cut 10 on the lower side of the line by using the adjustable stops 57 to 60 and the latch 62 in the lug 50. For marking on both sides 86 of the reference line at a single stroke, both latches 62 are retracted and a selected stop from each group of 15 stops is used. When each line has been completed, the coiled springs 30 raise the scribe pin 40 from the emulsified surface and resiliently press the bar 27 against the bracket 41, and at the same time the tension springs 72 return the 20 scribe pin 40 to the starting position.

At 81, Fig. 5, there is a typical showing of a scale of distances, while 88 is a glass plate negative on which lines are shown between which graduations are to be scribed. A plurality of 25 rubber suction cups 89 support my machine on a negative without injuring the surface.

My graduating device provides a means for readily adjusting the spacing of the "ticks" which varies progressively for each parallel of latitude 30 from the equator to the pole. After my machine has been adjusted as above outlined, it becomes a mere manual operation as my pivoted lever is successively released from one pin and locked to a selected succeeding one to produce neat, uniformly spaced graduations or "ticks."

I have shown and described one embodiment of my invention, but it is to be understood that it is capable of many modifications. Changes, therefore, in the construction and arrangement 40 may be made without departing from the spirit and scope of the invention as disclosed in the appended claims, in which it is my intention to claim all the novelty inherent therein as broadly as possible in view of the prior art.

What I claim is:

1. In a device of the class described, the combination with a suitable base provided with supporting suction cups, an extensible carriage mounted for reciprocating motion on said base and provided with a rack, a gear mounted on said base and engaging said rack, a telescoping lever having one member pivotally mounted on an upper one of said carriage sections, a plurality of space regulating pegs arranged in an arc on said upper carriage section, a pivoted claw member for selectively locking said pivoted lever member to said pegs, a transversely reciprocable bar mounted in a second portion of said carriage and pivotally connected to the second member of said telescoping lever, a second bar parallel to said first bar and connected thereto by links, a two-part scribe carriage mounted on said second bar, means for clamping said scribe carriage to said supporting bar and micrometer means providing limited movement between the main portion of said scribe carriage and a companion scribe holding portion, means for adjustably clamping said carriage sections to each other, means for reciprocating said carriage and attached scribe, 55 means for adjustably regulating the movement of said carriage and means for at will reciprocating said carriage for causing a scribe on said scribe carriage to cut graduations on a selected portion of said surface to be marked.
2. In a dividing engine provided with a suit-

able supporting base adapted for mounting upon a plane surface to be marked, selective means for regulating the lengths of graduations, and means for marking graduations on a selected side of a line, the improvement which comprises a reciprocable carriage comprising two overlapping sections, clamping means for coupling said sections together, a lever composed of two telescoping sections one of which is pivotally connected to one of said extensible carriage members, a plurality of spacing elements rigidly mounted on said member and means for selectively clamping a free end of said lever to one of said spacing elements.

3. In a graduating machine provided with a base adapted for mounting upon a plane surface to be marked, the combination with a carriage comprising two relatively movable sections, means for at will varying the effective length of said carriage, manually operated means for advancing said carriage with respect to said base, resilient means for retracting said carriage, a first lever section pivotally mounted on one carriage section, a second lever section telescopically connected with said first lever section, a plurality of spaced pins arranged in an arc extending upwardly from said one carriage section, a curved terminal claw on said first lever section adapted to be selectively locked to said pins, two latches and cooperating stops adapted to selectively limit the movements of said carriage, a plurality of adjustable stops to selectively limit the movement of the carriage, a carriage bar pivotally connected to the free end of the second carriage section and extending at right angles to the direction of reciprocation of said carriage, a scribe carriage slidably mounted on said carriage bar, a scribe pin adjustably mounted in said scribe carriage, means for adjusting said scribe pin and scribe carriage with respect to said carriage bar and resilient means for raising said carriage bar and scribe carriage.

4. In a device for marking flat surfaces with spaced graduation marks by means of a scribe or the like, the improvement which comprises a base, resilient suction cups for mounting said base over a selected portion of said surface, an extensible carriage comprising two relatively movable sections mounted on said base, means for reciprocating said carriage on said base, a plurality of space regulating pegs arranged in an arc on one of said carriage sections, a first lever section pivotally mounted on one section of said carriage, means for selectively locking said lever section to said pegs, a second lever section telescopically connected to said first lever section, a transversely reciprocable bar mounted on the other section of said carriage and pivotally con-

nected to the second lever section, a second reciprocable bar parallel to said first bar and connected thereto by links, a scribe carriage slidably mounted on said second bar, means for clamping said scribe carriage to said second bar, rack and gear means for adjusting the extension of said carriage, means for clamping said carriage sections in adjusted positions relative to each other, means for limiting the movement of said carriage with respect to said base, resilient means for raising said scribe and resilient means for returning said extensible carriage to initial position.

5. In a device for marking flat surfaces with spaced graduation marks by means of a scribe, the improvement which comprises a base, resilient suction cups for mounting said base over a selected portion of a surface, a carriage comprising two overlapping sections reciprocally mounted on said base, means for at will clamping said carriage sections together in selected relative positions, a plurality of spaced pegs rigidly mounted in the upper of said carriage sections, an extensible lever pivotally mounted on the upper of said carriage sections, a lever with a terminal claw pivotally mounted on one of said lever sections, a compression spring normally holding said claw in selected pin engaging positions, a transversely reciprocable bar mounted on the lower of said carriage sections and pivotally connected to a second section of said telescoping lever, a second bar parallel to said first bar and connected to said bar by links, a scribe carriage slidably mounted on said second bar, means for releasably connecting said scribe carriage with said second bar, a plurality of stops for selectively limiting the movement of said first carriage with respect to said base, a spring for raising said scribe carriage and for holding it raised, two tension springs for returning said extensible carriage to initial position, a rack on said upper carriage section, a pinion revolvably mounted on said base and in engagement with said rack, and an operating lever connected with 45 said pinion.
